UNITED STATES PATENT OFFICE.

GEORGE WHITE, OF ROCK ISLAND, ILLINOIS.

SEAT-BACK FOR VEHICLES.

SPECIFICATION forming part of Letters Patent No. 496,467, dated May 2, 1893.

Application filed November 10, 1892. Serial No. 461,548. (No model.)

To all whom it may concern:

Be it known that I, GEORGE WHITE, a citizen of the United States, residing at Rock Island, in the county of Rock Island and State 5 of Illinois, have invented certain new and useful Improvements in Seat-Backs for Vehicles; and I do hereby declare that the following is a full, clear, and exact description of the same, reference being had to the annexed drawings, 10 making a part of this specification, and to the letters of reference marked thereon.

This invention relates to certain new and useful improvements in spring backs for carriages and wagons, and it has for its objects 15 among others to provide a simple and cheap yet efficient construction whereby the desired result is obtained.

The objects and advantages of the invention will hereinafter appear and the novel 20 features thereof will be specifically defined by the appended claim.

The invention is clearly illustrated in the accompanying drawings, which, with the letters of reference marked thereon, form a part 25 of this specification, and in which—

Figure 1 is a perspective view of one form of my invention. Fig. 2 is a like view of another form.

Like letters of reference indicate like parts 30 throughout the several views in which they appear.

Referring now to the details of the drawings by letter, on reference first to Fig. 1, A designates the seat body and B the wooden 35 or metal back bar to the ends of which are secured the curved arms C, the ends of which project beyond the ends of the said bar and upon which are sleeved the ends of the rail arms D which are held thereon by suitable 40 means as nuts E; the other ends of the rail arms are secured to the sides of the seat in any well known way. The ends of the arms C should be provided with shoulders to limit the inward movement of the ends of the rail 45 arms. F are metal braces secured to the vertical portion a of the seat body and to their upper ends are hinged the lower ends of the

spring arms G which are secured at their upper ends to the cross bar B of the seat. The back of the seat is designed to be upholstered 50 and the upholstering will of course cover all of the parts above described, unless it be the rail arms.

In the form shown in Fig. 2 the back bar B and curved arms C are present and the rail 55 arms D are secured to the ends of the said curved arms by nuts E the same as in the form shown in Fig. 1, but the rail arms are integral with or rigidly secured to the metal frame H which is designed to be secured in 60 position in any well known way and is provided with the horizontal extensions or arms b and c to receive the bows and supports of the top, not shown. I are spring arms secured at their upper ends to the cross bar B 65 and at their lower ends to the rear cross rail H' of the said frame H as clearly seen in said Fig. 2.

In all of the forms shown the back possesses the necessary yielding ability to permit it to oscillate under pressure. The rail arms are practically spring arms and the whole back bar is resiliently mounted or supported. The result is a very easy seat back 70 and one which takes up or counteracts all jar 75 occasioned by the jerking movements of the horse or by running over uneven surfaces.

What I claim as new is—

The combination with the back bar of a seat, pivotally connected with some fixed 80 part, and the frame having the lateral extensions to receive the bows and supports of the top of the curved arms on the ends of the back bar and spring arm rails integral with the said frame and connected with the ends 85 of said curved arms, as set forth.

In testimony that I claim the above I have hereunto subscribed my name in the presence of two witnesses.

GEO. WHITE.

Witnesses:

JAS. S. WIVILL,
Mrs. C. H. LININGER.
